ELEVATABLE SCOOP CONTROL
MECHANISMEddie B. Wagner and Harold A. Wagner,
Portland, Oreg.

Application December 17, 1946, Serial No. 716,696

11 Claims. (Cl. 214—120)

1

The present invention relates to the art of handling materials, the invention comprising a material-handling machine, preferably the machine being of the automotive or self-propelling type. It is to be appreciated that the invention herein disclosed and claimed may be utilized in a stationary type of machine adapted to be permanently located in a single position or moved from place to place and fixed in locations of use, but that it is preferred that the invention be incorporated in an automotive vehicle.

The purpose of the present invention is to provide a new and improved mechanism for raising and lowering a material-handling device along a substantially vertical tower, the material-handling device being capable of substitution of one type for another type. For example, the device may comprise a scoop adapted to scoop coal, gravel, sand, grains and other materials of the same general nature, elevate the scooped load of material and transport it to another position or to a higher elevation, such as would be required for loading the material into a boxcar, or elevating materials to a building scaffold or the like. The material-handling device may, for example, be of the type commonly called a bucket, for the elevation of liquid or semi-fluid materials, such as concrete and the like, up to the elevated end of a material guiding trough such as is used for the emplacement of moist concrete in a building form. The material-handling device could comprise a platform for the elevation of bricks, stone or other building material to a building scaffold platform or into a boxcar or the like. It could comprise a fork such as is used for the collection of alfalfa, hay or other plant materials from a field and the depositing thereof in haymows or the like. The term "material-handling device" or "material-handling machine," as herein-after used in the specification and claims is, therefore, not to be limited to the specific form herein illustrated and described, the specific form being a scoop.

It is a principal object of the present invention to provide new and improved mechanism for controlling the material-handling device so that the device may assume a lowered, or inclined, or scooping position under the force of gravity, and the application of power to the device controlling mechanism will be effective first, to elevate the material-handling device to an upright or material carrying position, and thereafter to elevate the device along the tower upon which the device is guided for substantially vertical movement.

A further object of my invention is to provide

2

a carriage for pivotally supporting a material-handling device in off-center relationship so as to be inclinable by the force of gravity, and carriage elevating means comprising a cable and a cable-winding device having guiding means mounted on the carriage and about which the cable is passed.

A further object of the present invention is to provide a material-handling device adapted to be raised and lowered along a tower under control of a main cable adapted to be connected to an engine in the machine, the main cable being under control of a manual lever operatively interconnected with opposed action clutching and braking means whereby operation of the clutch to connect the cable to the engine simultaneously releases the braking means from the cable and vice versa.

A further object of the present invention is to provide a machine comprising a material-handling device adapted to be raised and lowered along a tower with means for arresting the movement of the device at any selected position, comprising a cable adapted to be wound and unwound from a drum under control of movement of the material-handling device and a brake under manual control adapted to arrest movement of the cable at any selected position.

A further object of the present invention is to provide, in a cable elevated material-handling device, means for the automatic arresting of the cable and holding of the material-handling device at a pre-selected point of elevation thereof.

A further object of the present invention is to provide a machine of the automotive type where in a material-handling device having the foregoing objects and advantages is adapted to be elevated by connection thereof to the engine which propels the vehicle from point to point.

The foregoing and other objects and advantages of my present invention will be apparent from an inspection of the following specification taken in connection with the accompanying drawings wherein like numerals refer to like parts throughout.

In the drawings Fig. 1 is a side view of an automotive machine having the present invention incorporated therein.

Fig. 2 is a front elevation of the machine taken from the plane defined by line 2—2 of Fig. 1.

Fig. 3 is a side elevation, partially in section, taken along the line 3—3 of Fig. 2.

Fig. 4 is a plan view, with parts broken away, taken substantially from the plane of the line 4—4 of Fig. 3.

55

Fig. 5 is a view in elevation, with parts broken away, taken substantially from the plane cut by the line 5—5 of Fig. 2;

Fig. 6 is a horizontal section taken from the line 6—6 of Fig. 5; and

Fig. 7 is a vertical section taken from the line 7—7 of Fig. 5.

The invention as illustrated and described comprises an automotive vehicle generally indicated by the numeral 10 having an engine therein for the purpose of propelling the vehicle from place to place and otherwise operating the material-handling device, the engine (shown in skeleton outline in Fig. 5) being connected to front driving wheels 11 mounted upon an axle extending from a transmission housing 14 in any of the usual manners. The engine is adapted to be connected to the wheels 11 through the medium of any usual transmission mechanism under control of a clutch (not shown) and a gear-shift lever 15, and the wheels are adapted to be locked in a selected position by braking means (not shown) under control of a brake-control mechanism exemplified by the brake lever 16. The vehicle may be steered from place to place by turning the single, centrally disposed, rear wheel 12, which is mounted on a fork 17 suitably supported on the body of the vehicle 10 and connected to a curved arm 18 having a tiller bar 19 suspended from its forwardly extending free end. The operator of the vehicle, seated in a seat 20, may at will connect the engine to the front driving wheels through the gear-shift lever 15, release the brakes through the brake lever 16, and steer the vehicle from place to place by shifting the tiller 19. It is to be appreciated that other forms or styles or designs of automotive vehicle may be substituted for the one herein illustrated without departing from my invention, or that the machine could comprise a semi-stationary, platform-mounted device without departing from the invention.

The machine comprises a substantially vertical tower, generally indicated by the numeral 25, including spaced upright angle bars 26 and 27 extending from a point near the ground adjacent the front of the machine to a suitable elevation above the body of the machine. The angle bars 26 and 27 comprise vertical guiding means for guiding a carriage 30 adapted to be raised and lowered along the tower, the carriage being provided with vertically spaced, flanged wheels 31 and 32 adapted to engage the opposite faces of the laterally disposed flanges of the bars 26 and 27, there being a pair of such wheels mounted at each side of the carriage, each pair engaging one of the upright guide bars. The bars are laterally braced by suitable cross members 34 at vertically spaced points and by a top cross member 35 adjacent the top of the tower. The tower also comprises members bracing the tower against movement longitudinally of the vehicle including members 36, 37 and 38 suitably attached to the body of the machine and at spaced vertical points to the upright bars 26 and 27.

The carriage 30 comprises side plates 40 upon which the guide wheels 31 and 32 are mounted and a substantially horizontal flange 41 extending between the plates 40 at a point near the top edges thereof. The lower extremities of the plates 40 extend forwardly and carry pintles 42 upon which a material-handling device, such as a scoop 43, is pivotally attached to the carriage. The material-handling device is mounted in an off-center relationship so that the center of

gravity thereof is forwardly of the pivotal mounting provided by pintles 42 so that the force of gravity may cause the material-handling device to tip forward to an inclined scooping position as indicated in skeleton outline in Fig. 3, or dumping position as shown in dash lines in Fig. 1.

A pulley 45 is mounted upon suitable journals (not shown) attached to the cross plate 41, the pulley being rotatable about an axis transversely 10 of the longitudinal center line of the machine and being suitably protected by a guard 46 extending above the plate 41. Beneath the pulley 45 there is a second pulley 48 mounted upon a horizontal transverse axle at a point slightly to 15 the rear of the axle of pulley 45, and a third pulley 49 is mounted upon a transverse axle extending between plates 50 and 51 depending from the cross member 35 near the top of the tower, the pulleys 45, 48 and 49 lying substantially in 20 the plane of the longitudinal axis of the machine. A main cable 55 has one end attached to a suitable clamp 56 mounted upon the rear wall of the material-handling device 43 at a point spaced from, and preferably above, the pivotal mounting 25 thereof. The cable 55 passes through an opening in the rear wall of the scoop, about the pulley 45, then down and around the pulley 48, up and around the pulley 49, and down to a drum device 60 mounted upon an axle 61 extending transversely of the machine, the axle being journaled 30 in the longitudinal side plates thereof and a central, longitudinally extending plate 62.

The drum 60 is keyed to the shaft 61 which is adapted to be rotated by a sprocket gear 63 and 35 a sprocket chain 64 passing about a sprocket gear 65 mounted upon a transverse axle 66 suitably mounted within the body of the machine. The axle 66 is connected through a worm and 40 gear device 67 to a shaft 68 extending longitudinally of the machine. The shaft 68 at its rear end carries one-half of a universal joint 69, the other half of which is carried by a substantially longitudinally aligned shaft 70 journaled in a journal 71 suitably supported in the 45 machine. The forward end of shaft 70 is fixed to a grooved collar 72 engaged by the pivot pins of a gimbal 73 which is pivotally attached to one 50 arm 75 of a toggle device having a second arm 76 pivotally attached to a boss on the journal 71. A toggle control lever 77 is pivotally attached to the pivotally joined ends of levers 75 and 76, extends through an opening in the side plate of the machine, and is pivotally attached to one 55 end of a bell crank 78 pivoted to the side plate, the opposite arm of which is pivotally attached to a longitudinally extending control rod 79. A spring 80, tensioned between an arm of the bell crank 78 and a suitable bracket on the side plate, tends to rock the bell crank 78 to the position 60 shown in Fig. 6 so as to cause the center joint of the toggle device to pass over-center in a clutch-releasing direction as illustrated in full line in Fig. 6. The rearward end of shaft 70 carries a cone clutch member 85 adapted to be 65 received in and clutchingly engage a conical cavity in the end surface of a plural-sheaved pulley 86, loosely journaled on the shaft 70, and about which are passed a plurality of V-belts 87 extending from a pulley (not shown) on the 70 crank shaft of the engine. Shifting of the toggle levers 75 and 76 to the positions shown in full outline in Fig. 6 causes shifting of the shaft 70 in a rearward direction, such shifting being permitted by a splined connection (not detailed) 75 of shaft 70 with the half of the universal joint

68 carried thereby. Such shifting of the lever causes disengagement of the clutch cone 85 from the pulley 36. Engagement of the clutch causes rotation of the shaft 68 and the drum 60, the direction of rotation being such as to wind the cable 55 upon the drum 60 and raise the carriage and material-handling device upwardly on the tower. Disengagement of the clutch is assured by the force of spring 80 which holds the toggle in releasing position.

In order to arrest the carriage at any selected position the control rod 79 is pivotally attached to an intermediate point of a lever 90 which is pivotally mounted at 91 on a suitable bracket 92, mounted on the side plates of the machine, and extending upward through a slot in the top plate of the machine to be engageable by the operator sitting in the driver's seat 20. The lever 90 carries an adjustable abutment screw 93 in position to engage a target 94 mounted upon one end of a lever 95 extending through the side plate of the machine. The inner end of the lever 95 is welded or otherwise rigidly fastened to a long vertical leg of a U-shaped rod 96, the rod 96 having a short vertical leg 97 which is free to pivot about the long leg as an axis of rotation. The long leg is journaled in pintle ears fixed to a bracket 98 suitably mounted upon the side plate of the machine. A spring 99 extends longitudinally of the machine and has one end affixed to an intermediate portion of the bar 95 and the other end fixed to a bracket 100 mounted upon the side plate, the spring always tending to rotate the target end of the bar 95 toward the rear of the machine and thus tending to rotate the short leg 97 of the U-bar to occupy a plane normal to the bracket plate 98. The leg 97 is pivotally attached to the free end of a brake band 101 passing about a brake drum 102 fixed to the shaft 68, so that when the leg occupies the plane normal to the bracket 98 the brake band 101 is tightened and the shaft 68 is held against rotation.

When the brake is released and the clutch disengaged, the work handling device, due to the force of gravity, may drop down along the tower at a speed controlled by the degree of loosening of the brake band 101 until a cross bar 105 on the carriage 40 engages a limiting cross bar 109 extending between the lower ends of the upright members 26 and 27, thus arresting the carriage. In the opposite direction of movement means are provided to prevent the carriage from overrunning the top of the tower. Such means comprise a cable 106 suitably clamped to the cross member 35 at one end, extending downward through a guide member 107 mounted upon the carriage, the cable for this purpose passing through a hole 108 in the top plate 41 of the carriage, and the free end of the cable passing back to be attached to the lever 90 at a point adjacent the attachment thereof to the push rod 79. When the carriage approaches the top of the tower the slack in cable 106 will be taken up by the cable being pulled outwardly in the hole 108 so as to apply tension thereto to shift the lever 90 forward to its center position, thus disengaging the clutch and engaging the brake on the mechanism operating the drum 60. It is to be appreciated that this automatic trip device may have application at any preselected point along the tower as by means of a limit member 110 adjustably clamped on cable 106 and adjustable longitudinally thereof so that the carriage will be automatically arrested at any preselected point.

The lever 90 has a lug 112 in position to engage

the lower end of a lever 113 pivoted on the machine, the opposite end of which carried an adjustable screw 114 opposite the face of target 94. Pulling back on lever 90 to engage the clutch causes screw 114 to rock the target forward, thus disengaging the brake.

If lever 90 is pushed forward from its central position continued movement of the toggle levers in unclutching direction results, thus releasing the brake due to screw 93 rocking the target 94. The springs 80 and 99 are so balanced that lever 90 is normally held in the intermediate position with the clutch disengaged and the brake engaged, and manual force is necessary to move it forward or backward.

Lever 90 thus has three positions; the forward position in which the clutch is released and the brake released, the intermediate position in which the clutch is released and the brake engaged, and the rearward position in which the clutch is engaged and the brake released. The intermediate position is normal and the lever tends to stay there so that manual force is necessary to move it to either of the other positions. The lever will not remain in the forward position unless it is manually retained, but it will remain in the rearward position due to spring 80 holding the toggle. When cable 106 is pulled by the carriage the springs will snap lever 90 to the intermediate position.

A second lever 120 is mounted alongside lever 90, the lever being pivoted at 121 so as to have a freely depending lower end. The lower end of the lever is pivotally connected to a rod 122 extending forward and pivotally attached to an intermediate portion of a toggle arm 123 pivoted at its upper end to a toggle arm 124 pivotally supported from the top plate of the machine. The free lower end of the arm 123 is pivoted to a rod 125 which is fixed to a shaft 126 journaled transversely of the machine. The shaft 126 has a short arm 127 fixed thereto which is pivoted to an upright adjustable rod 128 fastened to the free end of a brake band 129, the brake band passing about a brake drum 130 and fastened at its upper end to a bracket 131 depending from the top plate of the machine. Movement of the lever 120 forwardly of the machine pulls rearwardly on the rod 122 and causes toggle arms 123 and 124 to pass over-center, thus permitting a spring 132, tensioned between the rod 125 and the deck plate of the machine, to pull upwardly on rod 125 and rotate the shaft 126 through an arc of several degrees, thus pushing upward on the adjustable rod 128 and tightening the brake band 129 upon the surface of the brake drum 130 due to the tension of spring 132. When the lever 120 is pulled rearwardly the rod 122 pushes the toggle arms over-center in the opposite direction to the position shown in full outline in Fig. 3, the toggle arms being provided with limiting means (not shown) to prevent breaking thereof beyond the position illustrated so that the end of the brake band cannot be pushed upwardly and the drum will not be retained against rotation.

A cable 135 has one end clamped in a suitable clamp 136 upon the top plate 41 of the carriage and passes downwardly therefrom around a guiding pulley 137 suitably mounted on the front of the machine, the free end thereof being wound upon a portion of a drum device 138. A third cable 140 is suitably clamped by clamping means 141 upon a portion of the carriage 40 and passes upwardly and about a pulley 142 mounted alongside of pulley 49 near the top of the tower, the

other end thereof being passed about the drum device 138 in the opposite direction of winding from that of cable 135. The drum device 138 and the brake drum 139 are affixed to each other and journaled for loose rotation about the shaft 61. Therefore, as the carriage 40 mounts the tower the cable 135 will be unwound from the drum device and the cable 140 will be wound thereon, and vice versa. The braking of the drum device by the brake band 129 arrests the carriage at any preselected position of movement vertically of the tower.

Operation.—The operation of the present invention will be described in regard to a machine fitted with a scoop as illustrated. It is to be appreciated that the same operations may be performed with any other type of material-handling device. The operator may move the machine about by the normal use of the gear-shifting device exemplified by the lever 15, and the wheels may be locked by the brake device exemplified by the brake lever 16. Assuming that the carriage is at its lowermost position with the limiting members 105 and 109 in engagement, the operator may release the brake band 101 by moving the lever 90 forward, thus causing the scoop 43 to tip forwardly and downwardly under the effect of gravity. Since the brake band 101 no longer holds the shaft 61 against rotation, the cable 55 will unwind from the drum 60 and will be extended to the dotted line position shown in Fig. 3. Thereupon the operator may move the vehicle forward into piled materials, at the same time shifting the lever 90 rearwardly to engage the cone clutch device. The slack is taken up in the cable 55, the cable first raising the scoop 43 to its material-carrying or upright position, and thereafter, as the scoop comes into abutting relation with adjacent portions of the carriage 41, raising the carriage and scoop along the tower to the preselected position. For such raising movement the brake band 129 is released so that the drum device 138 rolls freely on the shaft 61 and winds the cable 140 thereon while permitting unwinding of the cable 135. At the proper elevation of the scoop the brake band 129 may be set to arrest the carriage at its preselected point or the lever 90 shifted to release the clutch and set the brake 101. Thereafter the operator may, if desired, move the vehicle to any other selected position for dumping the load. On arriving at such a position the transmission lever 15 is shifted to neutral, the brake 16 set, and dumping of the load achieved by loosening the brake band 101 under control of the lever 90. Since the brake band 129 remains set the carriage cannot move vertically but the scoop 43 will tip to its inclined position to dump the load either on the ground or at some elevated point, such as a concrete trough, boxcar or building scaffold. Thereafter lever 90 is shifted to clutch-engaging position whereupon the scoop will first be raised to its upright position and then the carriage will be raised to a further point unless prevented from doing so by the trip device including cable 106 which automatically releases the clutch and sets the brake band 101. The operator may, if desired, release the brake band 129 and move the lever 90 slightly forward, whereupon the carriage and scoop in the upright position will be lowered to the bottom of the tower due to the weight of the carriage and scoop overcoming the frictional force of the brake band 101.

Having illustrated and described a preferred embodiment which the invention may assume it

75 which said cable is passed, means clamping an

is to be appreciated that various modifications in detail and arrangement thereof may be achieved. All such modifications as come within the true spirit and scope of the appended claims are to be considered a part of our invention.

We claim:

1. A material-handling machine comprising a tower, a carriage guided for movement on said tower, means for raising and lowering said carriage along said tower comprising an engine and cable movable thereby, a material-handling device, such as a scoop, pivotally mounted on said carriage in off-center relation so as to be movable to a dumping or scooping position by the force of gravity, guiding means on said carriage about which said cable is passed, means for clamping an end of said cable to a portion of said material-handling device at a point spaced from the pivotal mounting thereof whereby slack in said cable 15 when said carriage is arrested permits movement of said material-handling device to scooping or dumping position and tightening of said cable first causes raising of said material-handling device to an upright or material-carrying position and thereafter causes raising of said carriage along said tower, a clutch for connecting said cable to said engine, a brake for arresting said cable, a lever, means connecting said lever to said clutch and to said brake for substantially simultaneously engaging said clutch and disengaging said brake upon movement of said lever to one position and for disengaging said clutch and engaging said brake upon movement of said lever to a second position, and means automatically to disengage said clutch and engage said brake as said carriage arrives at a preselected position on said tower.
2. An automotive vehicle having a tower mounted thereon, a carriage guided for movement along said tower, means connecting the engine of said vehicle to said carriage for raising and lowering it along said tower comprising a cable, a material-handling device pivotally supported on said carriage in off-center relation so as to be movable to an inclined position by the force of gravity, guiding means on said carriage about which said cable is passed, and means clamping an end of said cable to a portion of said material-handling device at a point spaced from the pivotal mounting thereof whereby slack in said cable permits movement of said device to its inclined position and tightening of said cable first causes elevation of said device to an upright or material-carrying position and thereafter causes raising of said carriage along said tower, said means connecting the engine of said vehicle to said carriage including a clutch and a brake, a manual lever operatively connected to said clutch, and means interconnecting said clutch and said brake for opposed functioning whereby when said clutch is engaged said brake is released and vice versa, said interconnecting means including a spring toggle device whereby said clutch is held in engagement.
3. An automotive vehicle having a substantially vertical tower mounted thereon, a carriage guided for vertical movement along said tower, means connecting the engine of said vehicle to said carriage for raising and lowering it along said tower comprising a cable, a material-handling device, such as a scoop, pivotally supported on said carriage in offset relation so as to be movable to a dumping or scooping position by the force of gravity, guiding means on said carriage about

end of said cable to a portion of said material-handling device at a point spaced from the pivotal mounting thereof whereby slack in said cable permits movement of said device to scooping or dumping position and tightening of said cable first causes elevation of said device to an upright or material-carrying position and, as soon as said device is brought into abutting relation with said carriage, raising of said carriage along said tower, said means connecting the engine of said vehicle to said carriage including a clutch and a brake, a manual lever operatively connected to said clutch, means interconnecting said clutch and said brake for opposed functioning whereby when said clutch is engaged said brake is released and vice versa, said interconnecting means including an over-center spring toggle device whereby said clutch is held in engagement, and a trip device connecting said carriage to said interconnecting means and operable automatically to disengage said clutch and engage said brake as said carriage approaches the top of said tower.

4. A material-handling machine comprising a substantially vertical tower, a carriage guided for vertical movement on said tower, means for raising and lowering said carriage along said tower comprising a cable, a material-handling device, such as a scoop, pivotally mounted on said carriage in offset relation so as to be movable to a dumping or scooping position by the force of gravity, guiding means on said carriage about which said cable is passed, means for clamping an end of said cable to a portion of said material-handling device at a point spaced from the pivotal mounting thereof whereby slack in said cable permits movement of said material-handling device to scooping or dumping position and tightening of said cable first causes raising of said material-handling device to an upright or material-carrying position and thereafter causes raising of said carriage along said tower, a second cable having one end attached to said carriage, a drum device mounted on said machine and upon which the other end of said second cable is wound, a third cable having one end attached to said carriage and its other end wound upon said drum device in a direction opposite to the direction of winding of said second cable, whereby elevation of said carriage winds one of said second and third cables upon said drum device and unwinds the other from said drum device and vice versa, and braking means including a manual lever to hold said drum device against rotation.

5. A material-handling machine comprising a tower, a carriage guided for movement on said tower, means for raising and lowering said carriage along said tower comprising a cable, a material-handling device pivotally mounted on said carriage in offset relation so as to be movable to an inclined position by the force of gravity, guiding means on said carriage about which said cable is passed, means for clamping an end of said cable to a portion of said material-handling device whereby slack in said cable permits movement of said material-handling device to its inclined position and tightening of said cable first causes raising of said material-handling device to a material-handling position and thereafter causes raising of said carriage along said tower, other cable means having attachment to said carriage, a drum device mounted on said machine and upon which said other cable means are wound, other guiding means about which said other cable means passes from said carriage to said drum device, said other cable means includ-

ing portions wound in opposite directions upon said drum device whereby elevation of said carriage winds one portion upon said drum device and unwinds another portion from said drum device and vice versa, and braking means to hold said drum device against rotation at any selected position.

6. An automotive vehicle having a substantially vertical tower mounted thereon, a carriage guided for vertical movement along said tower, means connecting the engine of said vehicle to said carriage for raising and lowering it along said tower comprising a cable, a material-handling device, such as a scoop, pivotally supported on said carriage in offset relation so as to be movable to a dumping or scooping position by the force of gravity, guiding means on said carriage about which said cable is passed, means clamping an end of said cable to a portion of said material-handling device at a point spaced from the pivotal mounting thereof whereby slack in said cable permits movement of said device to scooping or dumping position and tightening of said cable first causes elevation of said device to an upright or material-carrying position and, as soon as said device is brought into abutting relation with said carriage, raising of said carriage along said tower, said means connecting the engine of said vehicle to said carriage including a clutch and a brake, a manual lever operatively connected to said clutch, means interconnecting said clutch and said brake for opposed functioning whereby when said clutch is engaged said brake is released and vice versa, said interconnecting means including an over-center toggle device whereby said clutch is held in engagement, a trip device connecting said carriage to said interconnecting means and operable automatically to disengage said clutch and engage said brake as said carriage approaches a selected position on said tower, a second cable having one end attached to said carriage, a drum device mounted on said machine and upon which the other end of said second cable is wound, and a third cable having one end attached to said carriage and its other end wound upon said drum device in a direction opposite to the direction of winding of said second cable, whereby elevation of said carriage winds said second cable upon said drum device and unwinds said third cable from said drum device and vice versa, and braking means to hold said drum device against rotation.

7. An automotive vehicle having a tower mounted thereon, a carriage guided for movement along said tower, means connecting the engine of said vehicle to said carriage for raising and lowering it along said tower comprising a cable, a material-handling device pivotally supported on said carriage in off-center relation so as to be movable to a lowered position by the force of gravity, guiding means on said carriage about which said cable is passed, means attaching an end of said cable to a portion of said material-handling device whereby slack in said cable permits movement of said device to its inclined position and tightening of said cable first causes elevation of said device to an upright position and thereafter causes raising of said carriage along said tower, said means connecting the engine of said vehicle to said carriage including a clutch, a manual lever operatively connected to said clutch, means including a toggle device whereby said clutch is held in engagement or disengagement, a trip device connecting said carriage to said toggle device and operable auto-

matically to disengage said clutch as said carriage approaches a selected position on said tower, a second cable having one end attached to said carriage, a drum device mounted on said machine and upon which the other end of said second cable is wound, a third cable having one end attached to said carriage and its other end wound upon said drum device in a direction opposite to the direction of winding of said second cable whereby elevation of said carriage winds said second cable upon said drum device and unwinds said third cable from said drum device and vice versa, and braking means including a second manual lever to hold said drum device against rotation.

8. In a material-handling machine, a tower, a carriage movable substantially vertically of said tower, a pulley near the top of said tower, a second pulley mounted on said carriage, an engine associated with said machine, a scoop or the like pivotally mounted on said carriage so as to be movable to lowered or scooping position by the force of gravity, a cable attached at one end to said scoop, passed about said pulleys, and releasably connected to said engine at its other end, said cable being operative, therefore, upon being operatively connected to said engine, first to elevate said scoop from lowered or scooping position to an upright or material carrying position and thereafter to raise said carriage and said scoop along said tower, a second cable having one end attached to said carriage, a drum device mounted on said machine and upon which the other end of said second cable is wound, guiding means near the top of said tower about which said second cable passes from said carriage to said drum device, a third cable having one end attached to said carriage and its other end wound upon said drum device, other guiding means near the bottom of said tower about which said third cable passes from said carriage to said drum device, said second and third cables being wound upon said drum device in opposite directions whereby elevation of said carriage winds one upon said drum device and unwinds the other from said drum device and vice versa, and manually operable braking means to hold said drum device against rotation.

9. In a material-handling machine, a tower, a carriage movable along said tower, a pulley near the top of said tower, a second pulley mounted on said carriage, an engine associated with said machine, a material-handling device pivotally mounted on said carriage so as to be movable to an inclined position by the force of gravity, a cable attached at one end to said device, passed about said pulleys, and releasably attached to said engine at its other end, said cable being operative, therefore, upon being engaged to said engine first to elevate said device from its inclined position to an upright or material-carrying position and thereafter to raise said carriage and device along said tower, a second cable having one end attached to said carriage, a drum device mounted on said machine and upon which the other end of said second cable is wound, guiding means near the top of said tower about which said second cable passes from said carriage to said drum device, a third cable having one end attached to said carriage and its other end wound upon said drum device, other guiding means near the bottom of

said tower about which said third cable passes from said carriage to said drum device, said second and third cables being wound upon said drum device in opposite directions whereby elevation of said carriage winds one upon said drum device and unwinds the other from said drum device and vice versa, and manually operable braking means to hold said drum device against rotation.

10. A material-handling machine comprising a tower, a carriage guided for movement on said tower, means for raising and lowering said carriage along said tower comprising a cable, a material-handling device pivotally mounted on said carriage in offset relation so as to be movable to an inclined position by the force of gravity, guiding means on said carriage about which said cable is passed, means for clamping an end of said cable to a portion of said material-handling device whereby slack in said cable permits movement of said material-handling device to its inclined position and tightening of said cable first causes raising of said material-handling device to a material-handling position and thereafter causes raising of said carriage along said tower, other cable means having attachment to said carriage, a drum device mounted on said machine and upon which said other cable means are wound, and other guiding means about which said other cable means passes from said carriage to said drum device, said other cable means including portions wound in opposite directions upon said drum device whereby elevation of said carriage winds one portion upon said drum device and unwinds another portion from said drum device and vice versa.

11. In a material-handling machine an engine, a tower, a cable guided on said tower, a releasable clutch for connecting said cable to said engine, a brake for arresting said cable, a manual lever, means interconnecting said lever with said brake and said clutch including portions operative to release said brake and engage said clutch when said lever is shifted to a first position, to release said clutch and engage said brake when said lever is shifted to a second position, and to release said brake without affecting said clutch when said lever is shifted to a third position from said second position, a material elevating device connected to said cable and raised thereby along said tower when said lever is in said first position, and automatic means to move said lever from said first position to said second position when said elevating device reaches a preselected elevation.
